LOOSE LEAF BINDER

Edward A. Koelling, St. Louis, Mo.

Application October 15, 1938, Serial No. 235,126

6 Claims. (Cl. 129—17)

The present invention relates generally to loose leaf binders of the type in which certain prongs are movable longitudinally of the binder for the purpose of disposing sheets in different positions longitudinally of the binder, and more particularly to a locking and longitudinal shifting mechanism for maintaining the binder in its several operative positions and for permitting the longitudinal movement of certain binder prongs in one or more of such defined positions.

An object of the present invention is to provide a mechanism for locking a loose leaf binder in several positions and for permitting shifting of certain prongs relative to other prongs when the binder is in one or more of said positions.

Another object is to provide an improved novel locking mechanism for loose leaf binders.

Another object is to provide an improved novel prong-shifting mechanism for loose leaf binders.

Another object is to provide a locking mechanism which is adapted to hold a loose leaf binder in closed position, and which is adapted to define one or more semi-opened positions.

Another object is to provide a loose leaf binder of the prong-shifting type in which the central hinge is utilized as a shifting axis.

Another object is to provide a mechanism for loose leaf binders of the type in which certain prongs are shifted longitudinally of the binder which locks the prongs in closed non-shiftable position, and which locks or stops the prongs in partially opened shiftable relation.

Another object is to provide a sturdy, inexpensive, and simplified locking and shifting mechanism for loose leaf binders of the type in which certain prongs are shiftable longitudinally of the binder.

Other objects and advantages will be apparent from the following description, taken in conjunction with the accompanying drawings, in which:

Fig. 1 is a plan view of a loose leaf binder of the type in which certain prongs are shifted longitudinally of the binder relative to other prongs, a portion of one cover being broken away to disclose the type of sheets employed in such binders;

Fig. 2 is an end view of the binder shown in Fig. 1, a portion of the case being broken away to disclose features of the present invention as embodied in such binder;

Fig. 3 is a view of the binder shown in Fig. 1 showing the prongs in closed relation, the backs being spread open and broken away for conservation of space;

Fig. 4 is a view of the binder shown in Fig. 1

similar to Fig. 3 showing the prongs in partially spread disposition, parts of the case being broken away to disclose features of the present invention;

Fig. 5 is a view similar to Fig. 4 showing the right-hand series of prongs shifted upwardly relative to the left-hand series of prongs;

Fig. 6 is a view of the binder shown in Fig. 1 similar to those of Figs. 3 and 4 showing the prongs in fully opened position, parts being broken away to more clearly illustrate details of the present invention;

Fig. 7 is a section on the line 7—7 of Fig. 4;

Fig. 8 is an enlarged fragmentary section showing details of the locking mechanism;

Fig. 9 is a section on the line 9—9 of Fig. 8; and,

Fig. 10 is a fragment of a modified latch.

Referring to the drawings more particularly by reference numerals, 10 indicates generally a loose leaf binder of the prong-shifting type in which is incorporated the teachings of the present invention. The binder 10 includes a hinge construction 11, a front cover 12, and a rear cover 13.

The hinge construction 11 comprises a left-hand section 14 and a right-hand section 15 which are pivotally connected by a sectional hinge shaft 17 (Fig. 5) which includes hinge shaft segments 18 and 19. The shaft 17 may be integral, if desired.

The hinge section 14 includes a plate 20 which is folded to provide a central side 21, two sides 22 and 23 oppositely extending from the central side 21 (Fig. 7), the latter of which includes spaced looped segments 24 to receive the sectional hinge shaft 17, and end segments 25. A plate 26 is fixed to the plate 20, one side 27 thereof being welded or otherwise connected to the side 22 of the aforesaid plate 20. An angularly disposed side 28 of the plate 26 opposes the centrally disposed side 21 of the plate 20 to form, in effect, a box (Fig. 7). The side 27 includes spaced looped segments 30 which receive a hinge shaft 31. Spaced looped segments 33 of a plate 34 are interspersed with the looped segments 30. The cover 12 is fixed by means of rivets 35, or the like, to the plate 34. A strip 37 is welded or otherwise fixed in contiguous relation to the side 22. Evenly spaced arcuate prongs 38 are welded or otherwise fixed to the strip 37. Elongated apertures 39 are located in the strip 37 between the prongs 38 for the purpose of receiving the ends of prongs which will be described as part of the hinge section 15.

The cover 12 is fixed by means of rivets 35, or the like, to the plate 34. A strip 37 is welded or otherwise fixed in contiguous relation to the side 22. Evenly spaced arcuate prongs 38 are welded or otherwise fixed to the strip 37. Elongated apertures 39 are located in the strip 37 between the prongs 38 for the purpose of receiving the ends of prongs which will be described as part of the hinge section 15.

The right-hand hinge section 15 includes a plate 40 which is folded to provide a central side 41, two sides 42 and 43 oppositely extending from the central side 41 (Fig. 7), the latter of which includes spaced looped segments 44 to receive the sectional hinge shaft 17, and end segments 45 (Fig. 2). A plate 46 is fixed to the plate 40, one side 47 thereof being welded or otherwise connected to the side 42 of the aforementioned plate 40. An angularly disposed side 48 of the plate 46 opposes the centrally disposed side 41 of the plate 40 to form, in effect, a box (Fig. 7). The side 47 includes spaced looped segments 50 which receive a hinge shaft 51. Spaced looped segments 53 of a plate 54 are interspersed with the looped segments 50. The cover 13 is fixed by means of rivets 55, or the like, to the plate 54. A strip 57 is welded or otherwise fixed in contiguous relation to the side 42. Evenly spaced arcuate prongs 58 are welded or otherwise fixed to the strip 57. Elongated apertures 59 are located in the strip 57 between the prongs 58 for the purpose of receiving the ends of the prongs 38 forming a part of the hinge section 14. The hinge section 15 is adapted to be moved relative to the hinge section 14 longitudinally of the hinge shaft 17. The looped segments 44 are of a predetermined less width than the looped segments 24, although the space allowed for the looped segments 44 is equal to the width of the looped segments 24. The shifting space may be obtained by increasing the spaces between the looped segments 24 and increasing the looped segments 44 to equal the looped segments 24. The hinge shaft segment 18 is fixed relative to the looped segments 24 while the short hinge shaft segment 19 is fixed relative to a small looped segment 44 (Fig. 5). It is apparent from an inspection of Figs. 4 and 5 that the hinge section 15 can, therefore, be moved relative to the hinge segment 14 longitudinally from the position shown in Fig. 4 to the position shown in Fig. 5, and return.

A locking mechanism 63 is provided whereby the hinge sections 14 and 15 can be locked in the closed relation shown in Figs. 2 and 3, or restrained in the partially opened relation of Figs. 4, 5, and 7, or can be fully released to the position shown in Fig. 6. The base 64 of a bracket 65 (Figs. 7, 8, and 9) is fixed to the underside of the side 41 of the plate 40. A right-angular extension 66 of the bracket 65 is spaced from the inner side of the side 43, the extension 66 terminating in a lip 67 which substantially contacts the side 43. The bracket 65 is interiorly cut away at 68, part of the cut-away 68 lying in the base 64 and part in the extension 66, the cut-away being bounded on one side by a narrow strip 70 and on the other side by a narrow strip 71. The narrow strip 71 is disposed out of the plane of the base 64 and extension 66 in substantially arcuate configuration for a purpose to be described (Fig. 7).

A latch 73 is fixed to the underside of the side 21 and extends through a slot 74 (Figs. 5 and 7) in the side 23. The latch 73 includes an arcuate free section 75 contiguous to the outer end of which is an elongated slot 76 and an extension 77 having a shoulder 78. The latch 73 also includes an internally disposed shoulder 79 (Fig. 5).

A trigger or release member 80 (Figs. 2 and 6) extends along the interior face of the side 43 and through a notch 81 in the end 45 to terminate in a right-angular extension 82. The trig-

ger member 80 extends beneath the extension 66 of the bracket 65 and is cut away at 83 to clear the latch member 73 and to provide an edge 84 which is adapted to engage one or the other of the shoulders 78 and 79. A stop 85 (Fig. 8) struck upwardly from the trigger member 80 limits the downward movement of the trigger member 80 by its engagement with the edge of the extension 66. A helical spring 86 under tension extends between a projection 87 struck up from the base 64 and a projection 88 struck up from the trigger member 80 and biases the trigger member 80 into latching position.

In Fig. 10 is shown a modified latch 73' which differs from the latch 73 in having a notch 89 instead of a shoulder 78. The notch 89 cooperates with the edge 84 of the trigger member 80 to positively lock the hinge sections 14 and 15 in the positions shown in Fig. 4.

Operation

The present loose leaf binder 10 is adapted to hold short leaves 90 in spaced relation so that a line or two of legend is visible at the bottom. It is constructed to permit the insertion of a new sheet at any desired point and to permit the subsequent lowering of those sheets beneath the inserted sheet, or the raising of those sheets above the inserted sheet, to maintain the same spacing. This general principle of shifting one series of prongs of a book binder relative to another series of prongs is well-known; but heretofore the central hinge has not always been employed as the axis of shift. Further, a plurality of locking means has been required in previous constructions.

Assume that a new sheet is to be inserted in the place now occupied by the sheet designated A in Fig. 3. With the binder 10 in the position shown in Fig. 3, sheet A and those on top of sheet A are flipped to the right so that they rest upon the rear cover 13. The extension 82 is pressed inwardly to move the edge 84 out of engagement with the shoulder 79. This permits the hinge sections 14 and 15 to pivot around the hinge 45 shaft 17. Pressure is maintained on the extension 82 until the hinge sections 14 and 15 substantially reach a fully open relationship, such as is shown by Fig. 6, after which the pressure is released. A new sheet is inserted in the position formerly occupied by sheet A. The hinge sections 14 and 15 are then closed to the partially open position shown by Fig. 4, a position defined by the engagement of the shoulder 78 with the edge 84 of the trigger member 80, as is evident from an inspection of Fig. 4. With the hinge sections 14 and 15 in the position of Fig. 4, sheet A and the sheets below it are flipped back onto hinge section 14. Hinge section 15 is then moved relative to hinge section 14 into the position shown by Fig. 5. Sheet A and those sheets on top of it are flipped over onto hinge section 15, after which hinge section 15 is returned to the position shown in Fig. 4. Sheet A and the sheets below it are flipped back to hinge section 14 and the just-specified process is repeated if it is required that the sheets be two holes apart, as is shown by the drawings, for the shifting action accomplishes a one-hole movement only.

It is to be observed that the slot 76 engages the side 43 in the shifting movement of the hinge section 15. This engagement takes place before release of the shoulder 78 from the edge 84 so that a second locking mechanism is unnecessary. Further, it is to be observed that the latch 75

mechanism 63 is effective to lock the hinge sections 14 and 15 in the closed position of Fig. 3, or in the partially open position of Fig. 4. This simplified construction obviates the use of more than the one latch mechanism. It is, of course, to be understood that spaced latches may be used on large binders which are simultaneously operated by the same trigger member.

It is, of course, apparent that certain details of construction may be varied without departing from the spirit of the present invention. It is manifest that there has been described a book binder mechanism which fulfills all of the objects and advantages sought therefor.

It is to be understood that the foregoing description and accompanying drawings have been given by way of illustration and example and not for purposes of limitation, the invention being limited only by the claims which follow.

What is claimed is:

1. In a loose leaf binder, a hinge shaft, hinge sections pivotally mounted on said shaft by means permitting movement of one section relative to the other section along the shaft, means for preventing pivotal movement of said sections beyond a predetermined partially opened relation, and means for positively maintaining said sections in said partially opened relation during shifting of said one section relative to said other section, said second means comprising a portion of said first means.

2. In a loose leaf binder, a hinge shaft, hinge sections pivotally mounted on said shaft by means permitting movement of one section relative to the other section along the shaft, a latch fixed to one hinge section including a shoulder, and a releasable latch engaging member movably connected to the other hinge section, said shoulder being adapted to contact said releasable latch engaging member to prevent pivotal movement of said hinge sections beyond a predetermined opened relation, said latch also including an elongated slot adapted to engage the movable hinge section to permit a shifting of said movable hinge section in the predetermined partially opened relation.

3. In a loose leaf binder, a hinge shaft, cooperatively disposed hinge sections pivotally mounted on said shaft, one of said sections being

movable longitudinally of the shaft relative to the other section, means for locking said sections in closed relation, means for preventing movement of said sections beyond a predetermined partially opened relation, and means for positively holding said hinge sections in the predetermined partially opened relation during longitudinal shifting in that relation.

4. In a loose leaf binder, a hinge shaft, cooperatively disposed hinge sections pivotally mounted on said shaft, one of said sections being movable longitudinally of the shaft relative to the other section, means for locking said sections in closed relation, means for preventing movement of said sections beyond a predetermined partially opened relation, and means positively maintaining their relative opened positions during movement of one hinge section relative to the other hinge section along the hinge shaft as an axis of movement when said sections are in said partially opened relation, said three means including as a common element a latch member.

5. In a loose leaf binder, a hinge shaft, cooperatively disposed hinge sections pivotally mounted on said shaft, one of said sections being movable longitudinally of the shaft relative to the other section, means for locking said sections in closed relation, means for preventing movement of said sections beyond a predetermined partially opened relation, and means positively maintaining their relative opened positions during movement of one hinge section relative to the other hinge section along the hinge shaft as an axis of movement when said sections are in said partially opened relation, said three means including as a common element a latch member having two spaced shoulders and an elongated slot.

6. In a loose leaf binder, a hinge shaft, cooperatively disposed hinge sections pivotally mounted on said shaft, means for locking said sections in closed relation, means for locking said sections in a predetermined partially opened relation, and means positively maintaining their relative opened positions during movement of one hinge section relative to the other hinge section along the hinge shaft as an axis of movement when said sections are in said partially opened relation.

EDWARD A. KOELLING.
